GEORGE J. STADLER, OF BOSTON, MASSACHUSETTS, ASSIGNOR TO ARTHUR H. BAILLARD,
INCORPORATED, OF BOSTON, MASSACHUSETTS, A CORPORATION OF MASSACHUSETTS

LIQUID FUEL BURNER

Application filed June 13, 1928. Serial No. 285,038.

This invention relates to liquid fuel burners in which atomized oil or other liquid fuel is delivered to the combustion chamber of the heater, and has for its object the reduction to a minimum of the noise due to combustion which ordinarily accompanies the operation of such a burner and the increase in the efficiency of combustion.

In the operation of burners of this type, the most effective method of delivering the liquid fuel to the combustion chamber, particularly where the heavier fuel oils are employed, has been found to be through the use of an atomizing device from which the liquid fuel in a well atomized condition is delivered to the combustion chamber in the form of a diverging spray under a substantial initial velocity, relatively compact or condensed at and near the delivery device. Such delivery device, for example, is frequently in the form of an orificed nozzle through which the atomized fuel is discharged under substantial pressure, thereby producing a jet, which at and adjacent the nozzle is relatively compact, the most efficient form of jet or spray being one in which the liquid fuel is sub-divided into a large number of minute particles moving at a relatively high velocity on emergence from the nozzle or other delivery device. The supply of air necessary to effect and support combustion is ordinarily admitted at or about the delivery device, as, for example, at or about the mouth of the nozzle, and about the compacted portion of the jet or spray, the main air supply being thereby brought initially into contact with the atomized fuel where it is in its highly compacted and condensed state. This results in a noise of a roaring or reverberatory nature produced by the combustion of the fuel which is apart from any mechanical noise incidental to the operation of the pump, motor or other moving parts to supply the jet, and this noise, in spite of attempts to muffle or deaden it, is in many cases objectionable and detrimental. This method of air admission, moreover, results in more or less incomplete combustion of the fuel due to insufficient commingling of the air supply with the atomized particles of fuel, since a certain proportion of the

atomized particles moving at a relatively high velocity within the compacted portion of the jet or spray tend to be carried through and out of range of the air without intimate contact therewith and, impinging on the 65 walls or floor of the combustion chamber, tend to carbonize and form a deposit thereon.

The reverberatory roar or noise referred to appears to be due in large measure to the fact that the combustion which takes place between the small individual particles of liquid fuel and the auxiliary air supply is initiated in large measure near the delivery end of the jet or spray where the fuel particles are moving under a high velocity in a condensed and compacted state and in a relatively small, 60 restricted space. The gases resulting from such combustion being thus more or less confined in or about this compacted or condensed region, their sudden expansion following 70 combustion results in an infinite number of small explosions producing in the aggregate the reverberatory roar referred to.

I have found that by causing the main air supply to initially engage and commingle 75 with the atomized fuel relatively remote from the delivery device, and in the expanded part of the jet or spray where the latter has had opportunity to become enlarged and spread over a substantial area and where 80 liquid particles are themselves widely diffused, the commingling is spread over a wide area and the combustion is initiated and takes place throughout a large portion of the combustion chamber space. The gaseous 85 products of combustion between the individual fuel particles and the auxiliary supply being thereby relatively unconfined, their explosive character is substantially eliminated and the accompanying noise reduced to a 90 minimum. Instead of there being a central, well defined jet or spray of flame impinging against the walls of the combustion chamber accompanied by the roar referred to, the appearance is more nearly that of a solid mass 95 of flame spread uniformly throughout the combustion space, burning quietly and evenly.

The ideal condition is reached where each particle of atomized fuel, while still in mo- 100

tion and before contact with the walls of the combustion chamber, becomes surrounded by preferably preheated air, this resulting in a substantially complete and perfect combustion of the atomized fuel without carbonizing deposits and with the substantial elimination of all noise. This condition, I have found, is closely approximated by preheating the air supply and so directing it into the combustion chamber as to cause its wide diffusion throughout and to cause it initially to impinge on the jet or spray of atomized liquid fuel after the latter has itself become diffused and spread, but preferably while still traveling from the nozzle and prior to impinging against the walls of the combustion chamber.

The invention will be best understood by reference to the following description of one specific embodiment thereof, while its scope will be more particularly pointed out in the appended claims.

In the drawings:

Fig. 1 is a plan view of a liquid fuel burner employing one form of the invention, showing the relationship of a burner nozzle and air supply devices to the combustion chamber of a heater;

Fig. 2 is a central, sectional elevation taken through the combustion chamber of the heater on a slightly enlarged scale;

Fig. 3 is a plan view of the heater with the flooring of the combustion chamber removed; and

Fig. 4 is an end elevation of the nozzle showing the jet forming orifice.

Referring to the drawings and to the disclosed embodiment of the invention, there is shown for illustrative purposes a liquid fuel burner comprising a burner nozzle 11 provided with a jet forming orifice 13 (Fig. 4) which is preferably in the form of an elongated, horizontal slot, so that, viewed in elevation (Fig. 2), the jet formed thereby assumes a relatively flattened shape but, viewed in plan (Fig. 1), is relatively flared. Accordingly, while compact and condensed at the nozzle, the jet spreads laterally as it is projected through the chamber, as is indicated in Figs. 1 and 2. The invention, however, in its broader aspects is not limited to a jet or spray of any specific form.

For the purpose of illustration, the fuel supplied by the burner is herein assumed to be oil, although other liquid fuels may be employed.

Atomized oil is supplied to the nozzle by any suitable means, as, for example, through the delivery pipe 15, by a rotary pump (not shown) driven by the motor 17 and adapted to force a supply of commingled air and oil from the intermediate supply chamber 19 which draws its supply of fuel from a main reservoir or tank through the suction pipe 21.

While the specific construction of the means

adopted for supplying and forcing atomized fuel through the burner nozzle is unimportant, I have herein represented, without detailed illustration, as a typical example of such devices, the fuel feeding apparatus disclosed in the prior patent to Goodridge No. 1,631,859.

Referring to the heater with which the burner is associated, there is illustrated a combustion chamber 23 comprising a part of the heater 25 and having a wall lining 27 and floor 29 of refractory material. The heater may be of the hot water, steam or other type and may be of any desired shape or size, although an ordinary upright, round heater is herein shown for the purpose of illustration.

The nozzle 11 protrudes into the space of the combustion chamber through the casing 31 which carries the sparking electrodes 33 for the ignition of the fuel, and with the remainder of the combustion chamber, is preferably closed against the admission of any substantial supply of air, except as hereinafter described.

To provide the main supply of air for supporting the combustion of the oil, an air admission opening 35 is provided at the front of the heater below the nozzle 11 and between the chamber floor 29 and the base on which the heater rests. The air admission opening may be regulated by means of a damper 37.

The air admission opening 35 communicates with an air supply passage 39 extending from the front of the heater toward the rear thereof, the passage being partitioned off by bricking 41 from the space at either side thereof beneath the combustion chamber, so that the air is compelled to travel from the front toward the rear, and in its travel, during the operation of the burner, is preheated by contact with the heated flooring. At its rear end the passage 39 opens laterally in two branches 43 arranged to conduct the air back again toward the front of the combustion chamber at opposite sides of the passage 39.

To deliver the air to the combustion chamber, there are located in advance of the nozzle 11 beneath the flared or expanded portion of the jet, and herein substantially midway the length of the combustion chamber, a series of air delivery openings arranged in the floor 29, these being herein shown in the form of transverse slots, three in number, the middle one 45 of which extends across the width of the air passage 39 to receive air therefrom, while the remaining two slots 47 are positioned in substantial alignment with, but at opposite sides of, the slot 45 and communicate with the passages 43. The slots 47 have free communication with and extend laterally from the passages 43 and are of greater width than the central slot 45, here-

in extending approximately to the side walls of the combustion chamber.

The air entering through the admission opening 35, under the draft induced by the heater flue, flows through the passage 39 to the slot 45 where a portion is directed upwardly through the floor of the combustion chamber. The remainder of the air supply divides itself into two parts, returning 10 through the branches 43 to the slots 47 where it is also directed upwardly into the combustion chamber, forming, with the air from the slot 45, a sheet of air which strikes the atomized oil from beneath for substantially 15 the full width of the flared part of the jet.

The described passages are suitably partitioned off by suitable bricking from the rest of the space beneath the combustion chamber, so that the entire air supply entering the 20 passage 35 is confined to the paths presented by the passages 39 and 43 and, after being preheated by passing in contact with the heated walls of the combustion chamber, is caused to be delivered through the floor 25 slots.

The air supply, which is thus preheated and widely diffused across the combustion chamber on its entrance thereinto, is directed upwardly and impinges against the liquid oil while still traveling as a part of the jet and before the liquid particles have themselves impinged against the rear walls of the combustion chamber so that deposits of unconsumed fuel on the side walls or floor are 30 prevented. This contact between the air and atomized oil, however, is had initially in the expanded or flared part of the jet, so that the combustion is spread over a wide area of the combustion chamber and the gases of combustion are formed and allowed to expand in a relatively unconfined space. The fact that the contact between the upwardly moving air and the somewhat flared and flattened jet takes place where the liquid particles have lost 40 a large portion of their velocity also helps to increase the spread and diffusion of the commingled air and liquid oil particles over a still greater portion of the space of the chamber while the fuel is undergoing combustion. 45

50 Preferably the jet or spray for its full expanded area is met or overlapped by the air supply so that all of the atomized particles of oil contained within the jet or spray are obliged to impinge against the incoming air.

55 In the operation of the burner there is a slight tendency for some individual particles of oil to gravitate down from the jet and to reach the floor of the chamber between the nozzle and the air admission opening 45 and there carbonize and form an objectionable deposit. To insure the combustion of such particles as tend to gravitate from the jet, there is provided an auxiliary air supply which is admitted through a small slot 49 60 also communicating with the air passage 39

but located a short distance from the slot 45, between the latter and the nozzle 11. The small, limited air supply entering the slot 49 tends to be drawn toward the front of the combustion chamber, just above the floor 70 thereof, by the suction induced through the jet, where it encounters the gravitating particles of oil and commingles with the latter to initiate and promote the combustion 75 thereof.

The admission of air through the described arrangement not only reduces to a negligible amount the noise of combustion, which has heretofore characterized burners of this class, but also produces a more perfect and complete 80 combustion of the atomized oil, materially increasing the efficiency of the burner and eliminating the presence of smoke and soot in the flue.

The appearance of the combustion is more 85 nearly that of a solid mass of flame spread uniformly throughout the combustion space, burning quietly and evenly, the effect of the air admission being to throw the flame toward the front or nozzle end of the combustion 90 chamber as well as toward the sides and the back. This is of particular advantage in the case of boilers of the sectional or elongated type where oil burners have heretofore resulted in concentrating the flame at the rear 95 of the combustion space. Through the employment of the present invention all sections of the boiler, both front as well as rear, may be heated with substantial uniformity.

In connection with the described method of 100 supplying air to the combustion chamber, there is provided means which tends to cut off or reduce the air supply when the burner ceases operation, acting however to restore such supply as soon as it is required by the 105 starting up of the burner through the action of a house thermostat and insuring such air supply to the combustion chamber before any oil can be delivered to the chamber.

Herein for this purpose the damper 37 is 110 connected to a bell crank lever arm 61 having a link connection 63 to the lever arm 65 which is actuated by the solenoid magnet 67, the windings of which are in circuit with the motor 17. When the motor is deenergized the magnet will also be deenergized and the damper 37 drops by gravity to its closed position, thereby cutting off the air supply which would otherwise be drawn through the combustion chamber under the natural draft of 115 the chimney and tend to cool down more rapidly the heating medium contained within the heater. As soon as the house thermostat acts, however, to start up the burner, the magnet is energized and this serves to lift the damper to its open position, initiating the full air supply in advance of the time that any oil can be delivered through the nozzle. The fact that the damper controlling device 120 acts to open the damper simultaneously with 125

the energization of the motor renders it impossible for any oil to be delivered by the pump to the nozzle until after the air supply has been first provided.

While I have herein shown and described for the purpose of illustration one specific embodiment of the invention and one method of carrying it into effect, it is to be understood that extensive deviations may be made from the described form and arrangement of parts, and that the principles of the invention may be broadly applied to a wide variety of heaters requiring the admission of air to the combustion chamber under widely varying conditions and through widely varying means, all without departing from the spirit thereof.

What I claim is:

1. In a liquid fuel furnace, the combination with a heater having a combustion chamber provided with a floor, of a burner nozzle having a jet forming orifice, means for forcing a mixture of atomized liquid fuel under pressure through the orifice to form a jet within the combustion chamber over the floor, and an air admission passage formed beneath the floor for preheating the air, said passage having an air inlet at one side of the heater and extending thence across the heater beneath the floor and provided near the mid portion of the chamber with an air delivery opening through the floor and in line with the jet, said passage extending thence to the opposite side of the heater and thence reversely to an air delivery opening laterally positioned out of line with the jet and relatively remote from the nozzle and adapted to deliver air to the flared portion of the jet.

2. In a liquid fuel furnace, the combination with a heater having a combustion chamber provided with a floor, of a burner nozzle having a jet forming orifice, means for forcing a mixture of atomized liquid fuel under pressure through the orifice to form a jet within the combustion chamber over the floor, air delivery openings in the floor relatively remote from the nozzle, including an opening aligned with the jet and lateral openings at opposite sides thereof adapted to deliver air to the flared portion of the jet, and an air inlet passage extending beneath the floor from one side of the heater to said aligned delivery opening, thence to the opposite side of the heater and thence reversely through separated branches to said lateral delivery openings.

3. In a liquid fuel furnace, the combination with a heater having a combustion chamber provided with a floor, of a burner nozzle having a jet forming orifice, means for forcing a mixture of atomized liquid fuel under pressure through the orifice to form a jet within the combustion chamber over the floor, air inlet openings arranged in the floor including laterally positioned openings ar-

ranged to deliver air to the flared portion of the jet relatively remote from the nozzle, a second air opening aligned with the jet relatively nearer the nozzle, and an air inlet passage extending beneath the floor from one side of the heater and communicating first with said aligned air delivery opening, thence extending to the opposite side of the heater, and thence reversely through separated branches to said lateral air delivery openings.

In testimony whereof, I have signed my name to this specification.

GEORGE J. STADLER.
